(57) **CLAIM**

The ornamental design for an orally affixable palette shaped dental device, as shown and described.

DESCRIPTION

FIG. 1 is a perspective view of an orally affixable palette shaped dental device showing our new design;

FIG. 2 is a right side elevation view thereof, the left side being identical thereto;

FIG. 3 is a rear elevation view thereof;

FIG. 4 is a front elevation view thereof; and,

FIG. 5 is a top plan view thereof, the bottom plan view being identical thereto.
